(57) **CLAIM**

The ornamental design for a cosmetic applicator, as shown and described.

DESCRIPTION

FIG. 1 is a perspective view of a cosmetic applicator, embodying our new design;

FIG. 2 is a bottom view of the cosmetic applicator of FIG. 1;

FIG. 3 is a first side view of the cosmetic applicator of FIG. 1;

FIG. 4 is a top view of the cosmetic applicator of FIG. 1;

FIG. 5 is a second side view of the cosmetic applicator of FIG. 1;

FIG. 6 is a back view of the cosmetic applicator of FIG. 1; and,

FIG. 7 is a front view of the cosmetic applicator of FIG. 1. The broken lines illustrate portions of the cosmetic applicator and form no part of the claimed design.

1 Claim, 3 Drawing Sheets
